(57) **CLAIM**

The ornamental design for a razor, as shown and described.

DESCRIPTION

FIG. 1 is a perspective view of a razor of the present design;
FIG. 2 is a front view thereof;
FIG. 3 is a back view thereof;
FIG. 4 is a right view thereof;
FIG. 5 is a left view thereof;
FIG. 6 is a top view thereof; and,
FIG. 7 is a bottom view thereof.

The broken lines immediately adjacent the shaded areas represent the bounds of the claim. The remaining broken lines illustrate portions of the article. None of the broken lines form part of the claimed design. The lower lubrication bar shown with contour shading forms part of the claimed design.

It is understood that in FIGS. 1-7, the figure shading with cross-hatching represents a gold color. The lower lubrication bar is a white color.
